AGENT FOR WETTING, DISPERSING, ETC.

Heinrich Bertsch, Chemnitz, Germany, assignor
to H. Th. Bohme Aktiengesellschaft, Chemnitz,
Germany, a corporation of Germany

No Drawing. Application May 31, 1932, Serial
No. 614,613. In Germany November 7, 1931

14 Claims. (Cl. 252—1)

This invention relates to agents for wetting, purifying, washing, and dispersing purposes for use in the textile and other industries.

More particularly, it relates to tetrahydrofurfuryl alcohol and its adaptation with known treatment substances into commercial use as wetting, purifying, washing, or emulsifying agents.

The tetrahydrofurfuryl alcohol employed in the instant invention is preferably obtained by the catalytic hydrogenation of furfural in liquid phase in the absence of water and fractionally distilling to produce a condensate boiling between 170° and 180° C. This product is composed principally of tetrahydrofurfuryl alcohol but contains a small proportion of other reaction products.

Compositions composed of this tetrahydrofurfuryl alcohol product together with known treatment substances possessing, to various degrees, wetting, purifying, washing, or dispersing properties have proved quite successful in many branches of industry. The known treatment substances found satisfactory include solvents, soaps, and sulphonated oils, sulphuric derivatives of higher fatty alcohols, aromatic sulpho-acids, and their alkali salts.

Solvents found suitable for use with the tetrahydrofurfuryl alcohol include hydrocarbons such as benzene, benzine, tar oils and mineral oils; higher aliphatic, cycloaliphatic and aromatic alcohols, phenols; hydrogenated phenols such as cyclohexanol and methylcyclohexanol; ketones such as acetone and its higher homologues, cyclohexanone and aromatic and fatty-aromatic ketones; and halogenated hydrocarbons such as trichloroethylene and carbon tetrachloride. When the foregoing water insoluble liquids are mixed with the tetrahydrofurfuryl alcohol in preparing the composition, the former are brought by means of the latter into a state of minute subdivision.

The soaps that have been found to produce agents of exceptionally fine qualities include Marseilles soaps and grain soaps. As sulphonated castor oils there may be used e. g. sulphonated castor oil and sulphonated oleic acid, and as aromatic sulpho-acids, di-isopropylnaphthalene sulphonic acid and isobutylnaphthalene sulphonic acid.

Of outstanding effectiveness are the compositions containing with the tetrahydrofurfuryl alcohol, sulphuric derivatives (sulphonates and/or esters) of the higher fatty alcohols, and, in particular, the sodium or other alkali salts of the sulphuric derivatives of lauric alcohol.

The compositions containing the soaps, oils,

etc., above described, are most conveniently and advantageously used when made up in the liquid form in the manner in which liquid or dissolved soaps are found on the market.

In the place of tetrahydrofurfuryl alcohol, there may be used the tetrahydrofurfuryl esters of the lower aliphatic carboxylic acids, such as the acetic ester and the propionic ester.

The tetrahydrofurfuryl alcohol or ester may be used with complete success in admixture with insoluble substances, in particular, difficultly wetted powders, such as dyestuff powders, in the form of a paste. This paste, when later used for its intended purpose, readily disperses in water.

The outstanding success of the agents of the present invention is due in part to their high solvent and dispersing powers and their water solubility. Further, from an economical standpoint, the agents are much more desirable than the solvent and dispersing agents heretofore known. The extremely low cost of furfural and the inexpensive method, hereinbefore disclosed, of transforming the same into tetrahydrofurfuryl alcohol make the cost of the agents of the present invention most attractively low.

Examples

Example 1.—1 part of Marseilles soap is dissolved in 4 parts of tetrahydrofurfuryl alcohol. On dilution with water, this mixture yields clear solutions having excellent cleaning powers.

Example 2.—5 parts of tetrahydrofurfuryl alcohol are dissolved in 100 liters of water. This solution is adapted for the wetting of textiles.

Example 3.—2 kilograms of grain soap (60% fat content) are made into a solution with 10 kilograms of tetrahydrofurfuryl alcohol and 100 liters of water. This preparation is suitable for the removal of oil filaments containing mineral oil from textiles.

Example 4.—5 kilograms of the sodium salt of a sulphuric derivative of lauric alcohol are dissolved in 5 kilograms of tetrahydrofurfuryl alcohol and 500 liters of water. This solution is suitable for the washing of raw wool.

Example 5.—Equal parts of ethylene trichloride and tetrahydrofurfuryl alcohol are thoroughly mixed. This mixture is very satisfactory for the de-fatting of tanned sheep's hides.

Example 6.—20 parts of technical xylenols and 4 parts of tetrahydrofurfuryl alcohol are dissolved in 300 liters of sodium hydroxide solution of 30° Bé. The mixture is very well adapted for the mercerizing of cotton. Preliminary boiling of the fibrous material is not necessary, owing to the

excellent wetting properties of said mixture.

Having thus described the invention, what is claimed as new and desired to be secured by Letters Patent is:—

1. A composition of matter comprising, in combination, tetrahydrofurfuryl alcohol and a known treatment substance of a nature adapted for wetting, purifying, washing, or dispersing purposes.

2. An agent for wetting, purifying, washing, or dispersing purposes comprising, in combination, tetrahydrofurfuryl alcohol and a known solvent having wetting, purifying, washing, or dispersing properties.

3. The agent as described in claim 2 wherein the solvent is a phenol.

4. The agent as described in claim 2 wherein the solvent is xyleneol.

5. An agent for wetting, purifying, washing, or dispersing purposes comprising, in combination, tetrahydrofurfuryl alcohol and soap.

6. The agent described in claim 5 wherein the soap is a Marseilles soap.

7. An agent for wetting, purifying, washing, or dispersing purposes comprising, in combination, tetrahydrofurfuryl alcohol and a sulphuric derivative of a higher fatty alcohol.

8. The agent described in claim 7 wherein the derivative is an alkali salt of a sulphuric derivative of lauric alcohol.

9. A composition of matter comprising, in combination, a compound of the general formula

and a known treatment substance of a nature adapted for wetting, purifying, washing, or dis-

persing purposes in which R represents either a residue of a fatty acid having one to five carbon atoms or an atom of hydrogen.

10. The method of improving the wetting, dispersing, and penetrating properties of a liquid treatment agent which comprises adding thereto a compound consisting of tetrahydrofurfuryl alcohol combined as an ester with a lower aliphatic carboxylic acid. 80

11. The method described in claim 10 wherein the tetrahydrofurfuryl alcohol is combined as an ester of acetic acid. 85

12. The method of improving the wetting, dispersing, and penetrating properties of a liquid treatment agent which comprises adding thereto a compound consisting of tetrahydrofurfuryl alcohol. 90

13. The method of improving the wetting, dispersing, and penetrating properties of a liquid treatment agent which comprises adding thereto a reaction product composed principally of tetrahydrofurfuryl alcohol produced by the catalytic hydrogenation of furfural in the liquid phase in the absence of water, said reaction product boiling between 170° and 180° C. at 760 mm. pressure. 100

14. The method of improving the wetting, dispersing, and penetrating properties of a liquid treatment agent which comprises adding thereto a compound of the general formula

in which R represents either a residue of a fatty acid having one to five carbon atoms or an atom of hydrogen. 110
